UNITED STATES PATENT OFFICE.

GEORGE H. WOOD AND FRED L. CAPEN, OF BOSTON, MASSACHUSETTS.

SOLE-ASSORTING MECHANISM FOR BLOCK-SOLE-CUTTING MACHINES.

Application filed March 19, 1921. Serial No. 453,811.

To all whom it may concern:

Be it known that we, GEORGE H. WOOD and FRED L. CAPEN, citizens of the United States, residing at Boston, in the county of 5 Suffolk and State of Massachusetts, have invented new and useful Improvements in Sole-Assorting Mechanism for Block-Sole-Cutting Machines, of which the following is a specification.

- 10 This invention relates to machines for cutting block-soles, or soles which are cut to an approximation of their final shape by curved knives acting on a strip of sole leather, as described in various prior patents, and particularly the Knox Patent No. 558,964 of April 28, 1896, to which patent reference may be had for detailed description and construction of machines to which the invention appertains.
- 15 The machine includes a cutting bed and a pair of alternately acting knives having curved edges, and cooperating with the bed to cut alternating right and left soles from a strip of material moved over the bed, the 20 cut soles being caused to fall from the bed one by one, by the movement of the strip over the bed.

The object of the invention is to automatically separate the right soles from the left soles as they fall from the machine, so that the rights and lefts may be assembled separately without being manually assorted.

The invention is embodied in the improvements hereinafter described and claimed.

- 25 35 Of the accompanying drawings forming a part of this specification.—

Figure 1 is a side elevation of a block-sole-cutting machine and a sole-assorting or separating mechanism embodying the invention, associated therewith.

40 Figure 2 is a top plan view of the separating mechanism, a portion of the cutting machine being shown in section on line 2—2 of Figure 1.

- 45 Figure 3 is a side elevation of the sectional chute forming a part of the separating mechanism, and shown in end elevation in Figure 1.

Figure 4 is an end elevation of the chute.

50 Figure 5 is a side view of the front section of the chute and of the deflector hinged thereto.

Figure 6 is a side view of the rear section of the chute.

- 55 Figures 7 and 8 are perspective views of the chute sections.

Figure 9 is a perspective view of the deflector.

Figure 10 is a section on line 10—10 of Figure 3.

Figure 11 is a fragmentary plan view, and

Figure 12 is a fragmentary side view, illustrating portions of the mechanism for operating the deflector.

Figures 13 and 14 are fragmentary sectional views, illustrating the operation of the deflector.

The same reference characters indicate the same parts in all of the figures.

The cutting machine includes, as heretofore, a frame *a*, a cutting bed *b* thereon, beams *c* supporting the alternately acting curved knives *d*, *d*, oscillatory arms *f* secured to the beams, and the usual mechanism for raising and lowering the beams, the arms oscillating and causing the beams and knives to move in curved paths toward and from the cutting bed.

The two arms associated with each beam and knife are fixed to a tubular hub or sleeve *g* (Figures 11 and 12) mounted to turn on a transverse rod *h* fixed to the frame *a*.

We utilize one of the oscillating arms *f* to impart an oscillating movement to the deflector hereinafter described, through suitable connections constituting elements of our improved mechanism.

The soles as they are cut are pushed from the cutting bed by the advancing movement of the strip, and fall beside a fixed 90 apron *i* (Figure 1), at one end of the cutting-bed.

In accordance with the invention we provide a movable deflector 12, arranged to act on the falling soles, and means for moving 95 said deflector in timed relation with the knives to deflect the right soles in one direction, and the left soles in a different direction, so that the soles are caused to leave the machine in different paths, and are thus 100 automatically assorted, the rights being delivered at one point, and the lefts at a different point.

In the preferred embodiment of the invention here shown, the deflector 12 is 105 hinged at 13 to a fixed support which is a portion of the sole-guiding chute hereinafter described, and is connected with one of the arms *f* by mechanism which moves the deflector to the position shown by Figure 14, 110 when the knife *d* is raised, so that the deflector causes a sole falling from the bed

to move in the path indicated by the arrow y , and moves the deflector to the position shown by Figure 13, when the knife d is depressed, so that the deflector causes a sole falling from the bed to move in the path indicated by the arrow x .

The mechanism connecting the deflector with the arm f is preferably organized as next described.

- 10   Mounted loosely on the bearing stud h which supports the arms f is a relatively long lever 14, having a central enlargement containing an arcuate slot 15, the ends of which form stops 16, 16^a (Figure 12), preferably provided by blocks of fiber fixed in the end portions of the slot. Positively secured to one of the arms f is a shorter lever 17, preferably secured detachably, so that the mechanism now being described
- 15   20 may constitute an element of a sole-separating attachment readily applicable to an existing sole-cutting machine. With this end in view, we form the lever 17, so that it bears on one side of the arm f , as shown by Figure 11, and provide it with a clamp, composed of a plate 19, bearing on the opposite side of the arm and connected with the lever 17 by clamping bolts 20. The lever 17 is therefore positively oscillated with the arm f to which it is thus clamped.
- 25   30 The outer end of the lever 17 has a stud 21, which is movable in the slot 15, and abuts against the stops 16, 16^a alternately, to impart to the lever 14 movements of lesser amplitude than those of the lever 17. The outer end of the lever 14 is connected by a link 22 with the arms 23 of an angular lever, the other arm 24 of which is pivoted to oscillate on a fulcrum 25, supported by a
- 35   40 fixed arm 26 on the supplemental frame hereinafter described. The lever arm 24 is provided with a longitudinal dovetail groove, in which is fitted to slide a dovetail block 27 (Figure 11), having a stud 28, which is adjustable toward and from the fulcrum 25 by an adjusting-screw 29. A connecting-rod 30 is pivoted at one end to the adjustable stud 28, and at the opposite end to the deflector 12, the latter being provided with a pin 12^a, which enters an eye on the connecting-rod. Provision is thus made for oscillating the deflector, and for varying the amplitude of its movements by moving the stud 28 toward and from the fulcrum 25.
- 45   50   55 Although soles separated by the deflector may be delivered at different points by any suitable means, we prefer to provide means including a chute associated with the deflector and provided with two outlets, one arranged to guide the right soles, and the other the left soles, from the deflector, the preferred construction of said chute being next described.

- 60   65   65 The chute is of sectional construction,

and is composed of a rear section, indicated as a whole by 32 (Figures 4, 6 and 7), and a front section, indicated as a whole by 33, (Figures 4, 5, and 8), said sections being connected side by side by means such as straps 34 (Figure 4). The connected sections form two outlet portions 35 and 36, arranged in different planes (one offset from the other) and at opposite edges of the chute. The portion of the chute above 75 said outlet portions constitutes a receiving portion, communicating with each of the outlet portions, and arranged to receive all of the soles falling from the cutting bed.

The deflector 12 is connected by the 80 hinges 13 with the chute below the receiving portion, or at the junction thereof with the outlet portions, the hinges being supported by a member 37 of the section 33, constituting a septum or partition between 85 the two outlet portions, and forming an inner wall for each of said portions. The section 33 includes a member 37^a, constituting the outer wall of the outlet portion 36. The rear section 32 includes a sole-guiding 90 member extending from the upper to the lower end of the section, and having upper and lower inclined portions 38 and 38^a, and an intermediate vertical portion 38^b, the portion 38^a forming one wall of the outlet 95 portion 35. The outer wall of the outlet portion 35 is formed by the longer side of the section 32. (See Figure 7). The front section 33 includes a continuously inclined sole-guiding member 39, extending from the 100 upper to the lower end of the section and forming one wall of the outlet portion 36.

As shown by Figures 9 and 10, and by dotted lines in Figure 8, the deflector 12 constitutes a movable continuation of the 105 chute member or septum 37, and is adapted to guide soles falling into the receiving portion of the chute, to either side of said member. The deflector is preferably provided with a wing 12^a at one end, to aid 110 in guiding the soles when the deflector is in the position shown by Figure 13. The rear section 32 is provided with ears 41, arranged to rest on the upper edges of supplemental frame members 42, which are bolted at 43 115 (Figure 1), to the machine frame a . Pointed set screws 44 engaged with the ears 41 engage the upper edges of the frame members 42. The supplemental frame members project outward from the frame 12, and are 120 preferably supported in an inclined position, as shown by Figure 1, by legs 45, which may be of variable length.

The supplemental frame constitutes a support for the chute and for the arm or 125 standard 26, the latter being fixed to one of the frame members 42.

The soles delivered at different points by the two outlet portions of the chute may be disposed of in any suitable way. We prefer 130

to arrange said outlet portions over two conveyor belts 46, suitably spaced apart, the upper stretch of one belt being located under the outlet portion 35, while the upper stretch of the other belt is located under the outlet portion 36. Said belts are supported by pulleys 47 on shafts 48, journaled in bearings on the supplemental frame. Said shafts and pulleys are driven by any suitable means, such as a driving belt 49, running on another pulley 49^a on one of the shafts 48. The stretches of the belts between the pulleys are preferably inclined, as shown by Figure 1, the chute being located over the lower portions of the upper stretches, and the direction of movement of the belts being as indicated by the arrows in Figure 1.

The receiving portion of the chute is so arranged relatively to the cutting bed that the soles dropping from the bed enter the receiving portion about midway between the opposite ends thereof, so that they encounter the inclined chute member 38 in passing to the outlet portion 25, and the inclined chute member 39 in passing to the outlet portion 36, each of said members causing the falling soles to tip from a horizontal position, so that they fall endwise on to the belts and are caused to lie thereon with their major axes substantially parallel with the edges of the belts. The soles are thus adapted to be delivered endwise to a truck 50, stationed at the outer end of the supplemental frame, said truck having separate compartments into which the soles are delivered by the belts.

Idle rolls 51 on a shaft 52 journaled in bearings on the supplemental frame, bear on the upper stretches of the belts 46, and on soles carried by said stretches, and serve to exert a downward pressure on the soles, causing them to travel with the belt. The supplemental frame is provided with guard plates 53 (Figures 1 and 2), projecting above the upper stretches of the belts, and adapted to prevent the soles from falling over the edges of said stretches.

We claim:

1. In a sole-separating mechanism for block sole-cutting machines, in combination, a movable deflector, and means for connecting said deflector with a moving part of a cutting machine to cause the deflection of right soles in one direction, and of left soles in a different direction, so that the soles are conducted in different paths.

2. In a sole-separating mechanism for block sole-cutting machines, in combination, a movable deflector; means for connecting said deflector with a moving part of a cutting machine, to cause the deflection of right soles in one direction, and of left soles in a different direction; and a chute associated with the deflector, and provided with

a receiving portion and with two outlets, one arranged to guide right soles, and the other left soles, from the deflector.

3. In a sole-separating mechanism for block sole-cutting machines, in combination, 70 a movable deflector; means for connecting said deflector with a moving part of a cutting machine, to cause the deflection of right soles in one direction, and of left soles in a different direction, so that the soles are 75 conducted in different paths; a chute associated with the deflector, and provided with a receiving portion and with two outlets, one arranged to guide right soles, and the other left soles, from the deflector; and a 80 pair of conveyors arranged to receive soles delivered by the chute outlets, and to deliver the soles at different points.

4. A sole-separating attachment comprising a supplemental frame attachable to the 85 frame of a block sole-cutting machine; a movable deflector supported by said supplemental frame in position to act on soles falling from the cutting machine; and mechanism for imparting oscillating movements to the deflector, whereby the deflector may be moved to deflect right soles in one direction, and left soles in a different direction, said mechanism including an oscillatory lever, connections between the lever and the deflector, and means for securing the lever to a moving part of a cutting machine, to cause oscillation of the lever. 90

5. A sole-separating attachment comprising a supplemental frame attachable to the 100 frame of a block sole-cutting machine; a movable deflector supported by said supplemental frame in position to act on soles falling from the cutting machine; mechanism for imparting oscillating movements to the 105 deflector, whereby the deflector may be moved to deflect right soles in one direction, and left soles in a different direction, said mechanism including an oscillatory lever and means for securing the lever to a moving part of a cutting machine, to cause oscillation of the lever; and a chute supported by the supplemental frame and associated with the deflector, said chute being provided with two outlets, one arranged to 110 guide right soles, and the other left soles from the deflector. 115

6. A sole-separating attachment comprising a supplemental frame attachable to the frame of a block sole-cutting machine; a 120 movable deflector supported by said supplemental frame in position to act on soles falling from the cutting machine; mechanism for imparting oscillating movements to the deflector, whereby the deflector may be 125 moved to deflect right soles in one direction, and left soles in a different direction, said mechanism including an oscillatory lever and means for securing the lever to a moving part of a cutting machine, to cause 130

oscillation of the lever; a chute supported by the supplemental frame and associated with the deflector, said chute being provided with two outlets, one arranged to 5 guide right soles, and the other left soles, from the deflector; a pair of conveyor belts; and pulleys for said belts supported by the supplemental frame, said belts being arranged to support soles delivered by the 10 chute outlets, and to deliver the soles at one end of the supplemental frame.

7. In a sole-separating mechanism for block sole-cutting machines, in combination, an oscillatory deflector arranged to act on 15 soles falling from a cutting machine; a fixed support to which said deflector is pivoted; and deflector-oscillating mechanism, including a longer lever mounted to oscillate loosely, and having spaced apart stops between 20 its ends, a shorter lever having means for attachment to a moving part of a cutting machine, and having a stud movable between said stops to impart to the longer lever oscillating movements of lesser amplitude than 25 the movements of the shorter lever, and connections between the longer lever and the deflector.

8. In a sole-separating mechanism in combination, an oscillatory deflector arranged 30 to act on soles falling from a block sole-cutting machine; a fixed support to which said deflector is pivoted; and deflector-oscillating mechanism including a longer lever mounted to oscillate loosely, and having 35 spaced apart stops between its ends, a shorter lever having means for attachment to a moving part of a cutting machine, and having a stud movable between said stops to impart to the longer lever oscillating movements of 40 lesser amplitude than the movements of the shorter lever, and connections between the longer lever and the deflector, including a two-armed angular lever fulcrumed to a fixed support, and provided with a wrist-pin 45 which is adjustable toward and from the fulcrum, a link connecting one arm of the angular lever with the said longer lever, and a connecting rod pivoted at one end to the deflector, and at its other end to said 50 wrist-pin, the adjustability of said wrist-pin permitting variations of the amplitude of movement of the deflector.

9. In a sole-separating mechanism for block sole-cutting machines, in combination, 55 a sectional sole-guiding chute composed of a rear section and a front section connected side by side to form two outlet portions arranged in different planes and at opposite

edges of the chute, and an upper receiving portion communicating with each of the delivering portions, said sections including inclined sole-guiding members extending from the upper to the lower end of the chute, and forming inclined walls of both the receiving and the delivering portions; and a deflector 60 hinged to the chute below the receiving portion, and adapted to deflect soles entering the receiving portion into either of the delivering portions.

10. A sole-separating attachment for 70 block sole-cutting machines, comprising a supplemental frame, having means for attachment to the frame of a cutting machine, an oscillatory deflector supported by the supplemental frame, and deflector-oscillating 75 connections adapted to connect said deflector with a moving part of the cutting machine, and provided with clamping means adapted to be engaged with said moving part, and to impart movement therefrom to the deflector 80 through said connections.

11. A sole-separating attachment for block sole-cutting machines, comprising a supplemental frame, having means for attachment to the frame of a cutting machine, 85 a chute attached to the supplemental frame and having a receiving portion and two delivering portions, an oscillatory deflector hinged to the chute, and deflector-oscillating 90 connections adapted to connect said deflector with a moving part of the cutting machine, and provided with clamping means adapted to be engaged with said moving part, and to impart movement therefrom to the deflector 95 through said connections.

12. A sole-separating attachment for block sole-cutting machines, comprising a supplemental frame, adapted to be attached to the frame of the cutting machine, a chute attached to the supplemental frame and having 100 a receiving portion and two delivering portions, an oscillatory deflector hinged to the chute, deflector-oscillating connections 105 adapted to connect said deflector with a moving part of the cutting machine, and provided with clamping means adapted for engagement with said moving part, and a pair of conveyor belts carried by the supplemental frame, and arranged to support and carry soles delivered by the delivering portions of 110 the chute.

In testimony whereof we have affixed our signatures.

GEORGE H. WOOD.
FRED L. CAPEN.
